UNITED STATES PATENT OFFICE.

MELVIN L. STONE, OF LAWRENCE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed August 24, 1921. Serial No. 494,886.

To all whom it may concern:

Be it known that I, MELVIN L. STONE, a citizen of the United States, residing at Lawrence, in the county of Essex and State 5 of Massachusetts, have invented an Improvement in Feeler Mechanism for Looms, of which the following description, in connection with accompanying drawings, is a specification, like characters on the drawings representing like parts.

This invention relates to feeler mechanisms for looms, whereby the operative condition of the loom is changed as by replenishment of filling when the filling in the 15 shuttle becomes substantially exhausted.

The feeler mechanism of the present invention is of that general type wherein a feeler is moved in a direction longitudinally of the shuttle when the filling carrier 20 or bobbin in the shuttle has been substantially exhausted of filling.

When the replenishment is effected, the old filling carrier or bobbin is ejected from the shuttle, and a new filling carrier with 25 a supply of filling is placed in the shuttle.

The filling which remains on the old filling carrier or bobbin when it is ejected, constitutes waste, and on the other hand, if the filling carrier or bobbin becomes entirely denuded of filling before it is ejected and replaced by a full filling carrier or 30 bobbin, thin places are liable to be made in the cloth.

The feeler mechanism, therefore, must be 35 sensitive either to the presence or substantial absence of filling in the shuttle, and since minimum waste consistent with proper production of cloth requires that the filling carrier shall have a few turns 40 of filling on it when it is ejected, the sensitivity of the feeler must be such as to prevent its action until the critical point is reached, and then to insure its operation in calling for a change of filling.

The present invention provides a feeler 45 mechanism of the penetrating and impinging type, wherein the impinging feeler is moved longitudinally of the shuttle when the penetrating feeler is moved by engagement 50 with the surface of the bobbin or filling carrier. In carrying this feature of the invention into effect, the penetrating and impinging feelers are mounted on a carrier which is moved towards and from the front of the

loom, and on each detecting beat the penetrating feeler penetrates the filling, and the impinging feeler also meets the filling so long as a working supply is present in the shuttle. When, however, the filling approaches substantial exhaustion, the penetrating feeler will be struck by the more dense surface of the filling carrier or bobbin, and in case there is not sufficient filling in front of the impinging feeler as the lay beats up, the penetrating feeler will 60 act through a displacer to effect movement of the impinging feeler longitudinally of the shuttle, and thereby set into action a train of mechanism for effecting replenishment of filling.

In the drawings:

Fig. 1 is a plan view of a feeler mechanism embodying the present invention, and also showing a shuttle containing a working supply of filling, and the action of the 75 feeler as the lay beats up;

Fig. 2 is a plan view similar to that of Fig. 1, showing the same parts when, on a detecting beat the filling is approaching 80 substantial exhaustion;

Fig. 3 is a view similar to that of Figs. 1 and 2, showing the action of the feeler mechanism when the filling is substantially exhausted on a detecting beat;

Fig. 4 is a perspective view of the feeler 85 mechanism, some of the parts being broken away; and

Fig. 5 is an enlarged sectional view on the line 5—5 of Fig. 1.

The feeler mechanism of the present invention may be associated with a train of mechanism for effecting replenishment of filling, but such train of mechanism is not herein fully shown and described, because it forms no special part of the present invention, and is well known in the art. Therefore, only that portion of the train of mechanism which co-operates with the feeler mechanism of the present invention is shown.

The feeler is mounted for movement towards and from the front of the loom, and in the present instance, it is supported by a feeler stand 1 which may be secured to the loom frame by means of the screws 2 105 which pass through a slot 3 formed in the flange portion of the feeler stand. The feeler carrier 4 is mounted in the stand 1

for movement towards and from the front of the loom, and in the present instance is formed as a slide having a stem portion 5 which extends through an opening in the front portion of the feeler stand. Within the stand 1 as usual in this type of feeler carrier, there is a spring 6 which normally acts upon the feeler carrier 4 to hold it in its rearward position. An appropriate shoulder or stop 7 may conveniently limit the rearward movement of the feeler carrier under the dictates of the spring 6.

The feeler carrier 4 has mounted thereon a penetrating feeler and also an impinging feeler, the latter being mounted on the feeler carrier for movement in a direction longitudinally of the shuttle. A good form of the penetrating feeler is indicated in the drawings as comprising a pointed pin 8 which 20 extends rearwardly from a slide 9 mounted in the bearings 10 formed as part of or secured to the feeler carrier 4. It may be desirable in some instances to prevent rotative movement of the penetrating feeler slide 25 9 in its bearings 10, and one convenient means to this end is indicated in Fig. 4, wherein the penetrating feeler 9 is flattened and has a cap piece within the bearings held in co-operative relation with the feeler by 30 the set screws 12. The provision of means for preventing turning of the penetrating feeler is an extra precaution, and is not always needed.

The impinging feeler is mounted upon the 35 feeler carrier for movement in a direction longitudinally of the shuttle, and in the present instance, the feeler carrier is provided with a guideway substantially parallel to the longitudinal axis of the shuttle, and the impinging feeler is mounted for movement in the guideway. The guideway is preferably formed as a dove-tail slot 13, Fig. 4, which 40 extends crosswise of the feeler carrier 4, and the impinging feeler 14 has a dove-tail portion 15 which rides in a slot 13, the construction being such that the impinging feeler may move transversely of the feeler carrier, or in other words, in a direction longitudinally of the shuttle.

50 A feature of the present invention provides that the impinging feeler shall be restrained from movement in a direction longitudinally of the shuttle on a detecting beat when the working supply of filling is present 55 in the shuttle opposite the impinging feeler, notwithstanding the penetrating feeler may be struck by the surface of the filling carrier or bobbin, and for this purpose the impinging feeler is provided with a 60 series of teeth 16 which engage the filling in the shuttle on a detecting beat, and sink more or less into the filling, so that the impinging feeler is held from functioning movement in a direction longitudinally of 65 the shuttle as the filling approaches substan-

tial exhaustion, but before substantial exhaustion is actually reached, a condition graphically represented in Fig. 2.

Movement of the impinging feeler longitudinally of the shuttle in accordance with 70 the present invention, is effected through the action of the penetrating feeler which, when the penetrating feeler is moved forwardly on the feeler carrier or relatively to the impinging feeler, operates a displacer which 75 tends to move the impinging feeler longitudinally of the shuttle, and effects such movement only when the filling opposite the impinging feeler is substantially exhausted.

The penetrating feeler is normally held in 80 its rearward feeling position, as indicated in the drawings, by means of a spring 17, one end of which bears against a collar 18 fixed to the penetrating feeler, and the other end 19 of which finds a seat against the front 85 bearing 12.

As shown, the impinging feeler 14 is actuated from the penetrating feeler through the displacer, and in the present instance, the impinging feeler 14 has an upstanding pin 90 20 which engages the bifurcated end of a lever 21 pivoted at 22 upon the feeler carrier 4. The forwardly extending portion of the lever 21 constitutes an actuator 23, the end portion 24 of which is adapted to strike or 95 engage a transmitter 25 when the actuator is in operative position due to the impinging feeler having been moved by the displacer in a direction longitudinally of the shuttle.

A spring 26, Fig. 5, is utilized for normally 100 holding the impinging feeler in its initial feeling position. As shown, the spring 26 has a portion coiled about the pivotal support 22 which connects the lever 21 with the feeler carrier, and the end 27 of the spring 105 26 is engaged with the rearwardly extending portion of the lever 21, and normally holds the rear portion of the lever 21 against the stop pin 28, with the impinging feeler 14 in its normal feeling position.

110 The impinging feeler displacer, in the present instance of the invention, comprises an arm 29 which is extended from the penetrating feeler 9 and engages the laterally projecting portion 30 of the lever 21. The contacting portions of the arm 29 and the projection 30 may be provided with cam surfaces 31 and 32, the construction being such that when the penetrating feeler is moved forwardly by engaging the dense surface 115 of the filling carrier or bobbin, it will tend to effect movement of the impinging feeler in a direction longitudinally of the shuttle through the action of the displacer. If at such times, however, a working supply of 120 filling is carried by the shuttle opposite the impinging feeler 14, as indicated in Fig. 2, the teeth of the impinging feeler will engage the filling, and will prevent full movement of the impinging feeler longitudinally 125 130

of the shuttle in response to the penetrating feeler, and on forward movement of the feeler carrier, the end 24 of the actuator will pass the end of the transmitter 25 without actuating it. When, however, the filling has become so far exhausted that the few turns remaining on the filling carrier, as indicated in Fig. 3, are unable to resist the tendency to movement of the impinging feeler longitudinally of the shuttle due to the forward movement of the penetrating feeler, then the impinging feeler will move into the position indicated in Fig. 3 on a detecting beat, and the end 24 of the actuator will engage and move the transmitter 25, and through a well known form of mechanism, effect replenishment of filling.

The shuttle 33 may be of the usual type for supporting a filling carrier or bobbin 34, as by means of the usual holding jaws 35 and the bobbin rings 36, and it may also have its front wall slotted at 37 to permit the penetrating and impinging feelers to enter the shuttle on each detecting beat and perform their feeling functions.

From the construction described as one good practical embodiment of the invention, it will be observed that the penetrating feeler tends to effect movement of the impinging feeler in a direction longitudinally of the shuttle when the penetrating feeler engages the surface of the filling carrier or bobbin on a detecting beat, but that the impinging feeler is held from responding to the action of the penetrating feeler as long as sufficient filling is contained in the shuttle opposite the impinging feeler on a detecting beat, so that the teeth of the impinging feeler may be held by the filling and prevent full movement of the impinging feeler longitudinally of the shuttle. When the filling has reached a degree of substantial exhaustion, however, as indicated in Fig. 3, the few remaining coils of filling are unable to prevent movement of the impinging feeler longitudinally of the shuttle in response to the call of the penetrating feeler, and filling replenishment will be effected as hereinbefore described.

50 What is claimed is:—

1. In a feeler mechanism for looms, the combination of a penetrating and an impinging feeler mounted for simultaneous movement forwardly on a detecting beat until the filling is substantially exhausted whereupon the penetrating feeler engages the more dense surface of the filling carrier and is moved forwardly relatively to the impinging feeler, an actuating device that is moved by the penetrating feeler when it is engaged by the surface of the filling carrier on a detecting beat for effecting movement of the impinging feeler in a direction longitudinally of the shuttle, and means for replenishing the filling when the impinging

feeler responds to the actuating device on a detecting beat.

2. In a feeler mechanism for looms, the combination of an impinging feeler mounted for movement longitudinally of the shuttle, a penetrating feeler which is mounted to penetrate the filling on a detecting beat and move forwardly in unison with the impinging feeler and to be engaged by the more dense filling carrier as the filling approaches a condition of substantial exhaustion, and to be moved forwardly relatively to the impinging feeler, means connected to the penetrating feeler which tends to move the impinging feeler longitudinally of the shuttle when the penetrating feeler engages the filling carrier on a detecting beat and is held from effecting such movement of the impinging feeler until the filling opposite the impinging feeler is substantially exhausted.

3. A feeler mechanism for looms, comprising, in combination, a feeler carrier mounted for movement towards and from the front of the loom, a penetrating feeler mounted on the carrier, an impinging feeler also mounted on the feeler carrier for movement in a direction longitudinally of the shuttle, both of said feelers being moved forwardly in unison by working supply of filling on detecting beats and moved differentially forwardly when the filling is substantially exhausted and the penetrating feeler is struck by the more dense surface of the filling carrier, a displacer connected to the penetrating feeler tending to displace the impinging feeler in a direction longitudinally of the shuttle when the penetrating feeler is struck by the surface of the filling carrier on a detecting beat and held from effecting such displacing movement of the impinging feeler by engagement of the impinging feeler with the filling until the filling opposite the impinging feeler is substantially exhausted.

4. A feeler mechanism for looms, comprising, in combination, a penetrating feeler which penetrates the filling on each detecting beat and engages the surface of the filling carrier when the filling approaches substantial exhaustion, an impinging feeler movable in a direction longitudinally of the shuttle and having teeth which engage and sink into the filling on a detecting beat and hold the impinging feeler from movement longitudinally of the shuttle until the filling opposite the impinging feeler is substantially exhausted, and a displacer connected to the penetrating feeler for effecting movement of the impinging feeler longitudinally of the shuttle when the penetrating feeler is moved forwardly an increased amount relative to the impinging feeler the latter fails to be held by the filling.

5. In a feeler mechanism for looms, the

combination of a feeler mounted for movement in a direction longitudinally of the shuttle and held from such movement by engagement with the filling in the shuttle 5 on a detecting beat until substantial exhaustion thereof, a penetrating feeler mounted to penetrate the filling when a working supply is present in the shuttle on a detecting beat and as a result of such penetration to 10 move forwardly in unison with the impinging feeler and to be engaged by the more dense surface of the bobbin when the filling is substantially exhausted to effect forward movement of the penetrating 15 feeler relative to the impinging feeler, and means actuated by the penetrating feeler for effecting movement of the other feeler in a direction longitudinally of the shuttle when the filling is substantially exhausted on a 20 detecting beat.

6. In a feeler mechanism for looms, a toothed feeler mounted for movement in a direction longitudinally along the filling carrier and held from such movement by engagement with the filling on a detecting beat 25 until the filling is substantially exhausted, a penetrating feeler which penetrates the filling on a detecting beat and then moves forwardly in substantially unchanged relation with the toothed feeler and by engagement with the more dense filling carrier when the filling approaches exhaustion is given a forward movement with relation to the toothed feeler, and means for causing the relative forward movement of the 30 penetrating feeler to effect movement of the toothed feeler longitudinally along the filling carrier.

7. In a feeler mechanism for looms, the combination of a feeler carrier movable towards and from the front of the loom, a penetrating feeler mounted on the carrier, an impinging feeler mounted on the carrier for movement therewith and also in a direction longitudinally of the shuttle and having a connected actuator, a displacer connected to the penetrating feeler and rendered effective to move the impinging feeler longitudinally of the shuttle and operatively position the actuator when on a detecting beat the penetrating feeler is struck by the more dense surface of the filling carrier and is given an abnormal movement relative to the impinging feeler and the filling is substantially exhausted.

8. A feeler mechanism for looms, comprising, an impinging feeler that is moved forwardly on each detecting beat and is mounted for movement in a direction longitudinally of the shuttle, an actuator that is controlled as to its operation by movement of the impinging feeler longitudinally of the shuttle, a penetrating feeler that has a normal forward movement with the impinging feeler when a working supply of

filling is in the shuttle on a detecting beat and is abnormally displaced forwardly relative to the impinging feeler by contact with the advancing filling carrier when the filling is substantially exhausted on a detecting beat, a displacer operated by the abnormal relative movement of the penetrating and impinging feelers for moving the impinging feeler longitudinally of the shuttle, and a transmitter that is actuated by the operatively positioned actuator.

9. In a feeler mechanism for looms, the combination of a feeler carrier that is moved forwardly on each detecting beat, a penetrating feeler yieldingly mounted on the feeler carrier, an impinging feeler mounted on the feeler carrier for movement therewith and also in a direction longitudinally of the shuttle, both of said feelers having a normal forward movement on a detecting beat until the filling is substantially exhausted and then having an abnormal relative movement due to the engagement of the penetrating feeler with the more dense surface of the filling carrier an impinging feeler displacer which tends to move the impinging feeler longitudinally of the shuttle when the penetrating feeler is abnormally displaced forwardly by contact with the advancing filling carrier on a detecting beat, an actuator which is operatively positioned by the displaced impinging feeler, and a transmitter adapted to be operated by the actuator.

10. In a feeler mechanism for looms, the combination of a feeler carrier that is moved forwardly on each detecting beat, a penetrating feeler mounted on the feeler carrier, an impinging feeler mounted on the feeler carrier for sliding movement in a direction longitudinally of the shuttle, an actuator connected to the impinging feeler to be operatively positioned thereby when the impinging feeler is moved on the feeler carrier in a direction longitudinally of the shuttle, a transmitter which is operated by the operatively positioned actuator, and an impinging feeler displacer which effects movement of the impinging feeler longitudinally of the shuttle when the penetrating feeler is moved relatively to the feeler carrier by the advancing filling carrier on a detecting beat.

11. In a feeler mechanism for looms, the combination of a feeler carrier having a guideway extending in a direction longitudinally of the shuttle, an impinging feeler mounted for sliding movement in the guideway and having filling engaging teeth, an actuator connected to the impinging feeler, a transmitter, a penetrating feeler mounted on the feeler carrier, and a displacer actuated by the penetrating feeler when it is moved forwardly on the feeler carrier on a detecting beat for moving the impinging

feeler longitudinally of the shuttle and operatively positioning the actuator.

12. In a feeler mechanism for looms, the combination of a feeler carrier, a penetrating and an impinging feeler both mounted on the feeler carrier for normal movement together on each detecting beat, and an impinging feeler displacer rendered effective by abnormal frontward movement of the 10 penetrating feeler relative to the feeler carrier by engagement with the advancing filling carrier on a detecting beat for moving the impinging feeler on the feeler carrier in a direction longitudinally of the shuttle 15 when the filling is substantially exhausted opposite the impinging feeler.

13. In a feeler mechanism for looms, the

combination of a penetrating and an impinging feeler mounted for movement toward the front of the loom in normal relative positions on a detecting beat until the filling is substantially exhausted whereupon the feelers are caused to move relatively in a frontward direction into abnormal relation by engagement of the penetrating feeler 25 with the more dense surface of the filling carrier, and means actuated by such abnormal frontward relative movement of the feelers for effecting movement of the impinging feeler longitudinally of the shuttle. 30

In testimony whereof, I have signed my name to this specification.

MELVIN L. STONE.
